UNITED STATES PATENT OFFICE

149,877

DESIGN FOR A CLOTHESPIN

Orric V. Johnson, Erie, Pa.

Application February 15, 1947, Serial No. 136,925

Term of patent 14 years

(Cl. D17—6)

To all whom it may concern:

Be it known that I, Orric V. Johnson, a citizen of the United States of America, residing at Erie, in the county of Erie and State of Pennsylvania, have invented a new, original, and ornamental Design for a Clothespin, of which the following is a specification, reference being had to the accompanying drawing, forming part thereof.

In the drawing

Fig. 1 is a side elevational view of a clothespin, showing my new design;

Fig. 2 is an elevational view at right angles to the disclosure in Fig. 1; and

Fig. 3 is a top plan view thereof.

I claim:

The ornamental design for a clothespin, as shown.

ORRIC V. JOHNSON.
